UNITED STATES PATENT OFFICE

90,514

DESIGN FOR A TEXTILE FABRIC OR SIMILAR ARTICLE

Michelangelo A. Susi, New York, N. Y., assignor to Goldstein-Wilkins Corporation, New York, N. Y.

Application June 27, 1933. Serial No. 48,548

Term of patent 3½ years

To all whom it may concern:

Be it known that I, MICHELANGELO A. SUSI, a citizen of the United States, residing at 448 Central Park West, New York, New York, have invented a new, original, and ornamental Design for a Textile Fabric or Similar Article, of which the following is a specification, reference being had to the accompanying drawing, forming a part thereof.

The figure is a plan view of a textile fabric showing my new design.

I claim:

The ornamental design for a textile fabric or similar article as shown.

In testimony whereof I have signed this specification.

MICHELANGELO A. SUSI.
